UNITED STATES PATENT OFFICE.

LOUIS J. CONTRESSA, OF BROOKLYN, NEW YORK, ASSIGNOR TO STERLING BAG COMPANY, INCORPORATED, A CORPORATION OF NEW YORK.

DOUBLE-END BAG-TURNING MACHINE.

Application filed July 24, 1925. Serial No. 45,838.

This invention relates to a double end bag turning machine.

The object of the invention is the production of a bag turning machine, with which 5 bags can be turned outside in or vice versa by mechanism at both of its ends. A second object of the invention is the production of a machine in which the essential elements thereof are adjustable. The third object of 10 the invention is the production of a machine for turning bags which is composed of simple parts that can be easily repaired or replaced.

The organization of the invention comprises a reciprocating cross head on which 15 are pivoted two pairs of bell crank levers. Each pair of bell crank levers have adjustably connected thereto a pair of oppositely positioned turning rods for opposite ends of 20 the machine. Each bell crank lever has adjustably connected thereto a roller, which coacts with a track to swing and maintain each bell crank lever in proper position as the cross head reciprocates. The tracks are 25 adjustably connected to the frame of the machine, which with the adjustable feature of the rollers of the bell crank levers provides two adjustments for the movements of the turning rods.

30 Fig. 1 represents a side elevation of an exemplification of the double end bag turning machine; Fig. 2 shows a top plan view of Fig. 1 with some parts removed; Fig. 3 is an enlarged section of Fig. 1 on the line 3, 3; 35 Fig. 4 indicates an enlarged fragmentary portion of Fig. 1; Fig. 5 is a top plan view of Fig. 4 and Fig. 6 is a section of Fig. 4 on the line 6, 6.

The improved double end bag turning 40 machine is shown in this instance to comprise a pair of end frames, shown in their entireties respectively at A and B, connected by the runway frame designated in its entirety by the letter C.

45 The frames A and B each consist of the vertical corner posts 20 and 21, connected by the upper side beams 22 and 23, and the upper cross beams 24 and 25. The corner posts are connected by the lower side beams 50 26. Vertical posts 30 and 31 extend from each of the cross beams 25, and are in turn connected by the cross pieces 32 adjacent to their lower ends. Cross pieces 33 extend between the lower portions of the posts 30,

31 and the corner posts 21. Cross tie bolts 55 34 extend through the posts 21, 30 and 31.

The runway frame comprises the two upper longitudinal beams 38 preferably of metal, which extend between and are connected to the cross beams 25, and the lower 60 longitudinal beam 39 which extends between and is connected to the cross pieces 32.

Brackets 42 extend up from the beams 38 and support the feed table 43. The bags to be turned are located one over the other 65 on the table 43.

Brackets 50 extend up from the side beams 22 and 23 of the frame A. An oscillating shaft 51 is supported in the upper portions of the brackets 50, and a second oscillating 70 shaft 52 is supported in said brackets 50 below the shaft 51. Brackets 53 are fastened to the shaft 51 and have in turn fastened thereto the U shaped bag supporting bracket 54. Brackets 55 similar to 53 are fastened 75 to the shaft 52, and have each extending therefrom a D shaped arm 56. An arm 59 extends from the shaft 51, a rod 60 has one end pinned to the arm 59 and its other end extends through an opening in the guide 80 bracket 61 extending from the beam 23, of the frame A. A spring 63 encircles the link 60 with one end fastened thereto and its other end bears on the bracket 61. An arm 65 has one end fastened to the shaft 52. A 85 connecting rod 66 with the enlarged portion 67, has the upper end of the latter pinned to the arm 65. A bracket 71 has its upper end fastened to the beam 22 and at its lower end is formed a flange 72. The 90 latter has an opening through which extends the connecting rod 66. A spring 73 extends between the enlarged portion 67 of the rod 66 and the flange 72. A bracket 95 74 extends from one of the posts 21 of the frame A and has extending therefrom a pin 75. To the latter is pivoted the lever 76. The lever 76 has pivoted to one end the lower end of the connecting rod 66, and to the other end is journaled the roller 77.

100 A driving shaft 78 has one end journaled in the journal bracket 79 extending from one of the posts 21 of the frame A. A journal bracket 80 with the journal bearings 81 and 82, extends from the post 31 of the frame A. The other end of the shaft 78 is journaled in the bearing 81. A pulley 83 is fastened to one end of the shaft 78, and a

pinion 84 is fastened to the other end of the said shaft. A bevel pinion 85 is also fastened to the shaft 78. A journal bracket 86 is fastened to the post 21 of the frame A, 5 and a journal bracket 87 is fastened to the post 31 of the frame A. A shaft 90 is journaled in the journal brackets 86 and 87. A spur gear 91 is fastened to the shaft 90 and meshes with the pinion 84. A connecting 10 rod 95 has one end pivoted to the spur gear 91 by means of the pin 96. Cams 97 and 98 are fastened to the shaft 90. The cam 97 coacts with the roller 77 of the lever 76. A lever 100 is pivoted on the pin 75. A 15 bracket 101 has one end fastened to the lever 100. A rope 102 has one end fastened to the lower end of the bracket 101. A roller 103 is journaled to the lever 100 and coacts with the cam 98. A pair of similar 20 journal brackets 104, each with an elongated slot 105 are adjustably fastened to the beams 22 and 23 by the bolts 106. The brackets 104 have supported therein the oscillating shafts 108 and 109. A lever with the arms 25 110 and 111 is fastened to the shaft 108. The rope 102 has one end fastened to the arm 110. A spring 114 has one end fastened to the arm 111 and its other end is fastened to the bracket 115 extending from 30 the beam 22 of the frame A. A segmental gear 116 is fastened to the oscillating shaft 108, and a segmental gear 117 is fastened to the oscillating shaft 109, and the teeth of the latter mesh with the teeth of the former. A pair of clamping fingers 118 extend from the shaft 108 and a pair of co- 35 acting clamping fingers 119 extend from the shaft 109.

To the post 30 of the frame B is fastened 40 the journal bracket 124 with the journal bearings 125 and 126 and to one of the posts 21 of the frame B is fastened the journal bracket 128. A shaft 130 is journaled in the journal bracket 128 and in the journal bearing 125.

A bevel gear 132, is fastened to the shaft 130. An inclined shaft 133 has its ends journaled in the journal bearings 82 and 50 126. A bevel gear 134 is fastened to one end of the shaft 133 and meshes with the bevel pinion 85, and a bevel pinion 135 fastened to the other end of the shaft 133 meshes with the bevel gear 132.

To one of the posts 21 of the frame B is 55 fastened the bracket 140 similar to 74 and from which extends the pin 141. To the shaft 130 is fastened a cam 142 similar to 97. To one end of the pin 141 is fastened the lever 143 similar to 76. The lever 143 has journaled to one end thereof the roller 144 which coacts with the cam 142. A pair 60 of brackets 147 similar to 50 are supported upon and fastened to the beams 22 and 23 of the frame B, and have supported therein the oscillating shafts 148 and 149, respec- 65

tively similar to the shafts 51 and 52. Brackets 153 similar to 53 are fastened to the shaft 148 and have in turn fastened thereto the U shaped supporting bracket 154 similar to 54. Brackets 155 similar to 70 55 are fastened to the shaft 149, and each have extending therefrom a D shaped arm 156 similar to 56. An arm 159 similar to 59 extends from the shaft 148, and a rod 160 similar to 60 has one end pinned to the 75 arm 159, and its other end extends through an opening in the guide bracket 161 extending from the beam 22 of the frame B. A spring 163 similar to 63 has one end fastened to the rod 160 and its other end bears 80 on the bracket 161. An arm 165 has one end fastened to the shaft 149. A connecting rod 166 similar to 66 with the enlarged end 167 has its upper end pinned to the arm 165. A bracket 171 similar to 71 has its upper 85 end fastened to the beam 23 of the frame B, and to its lower end is formed the flange 172 similar to 72. The flange 172 has an opening through which extends the connecting rod 166. A spring 173 similar to 73 extends between the enlarged end 167 of the rod 166 and the flange 172. The lower end of the latter connecting rod is pivoted to the lever 143.

To the pin 141 is fastened the lever 180 95 similar to 100, to one end of which is journaled the roller 183 similar to 103. A cam 184 similar to 98 is fastened to the shaft 130 and coacts with the roller 183. A bracket 185 extends from the lever 180. A rope 186 similar to 102 has one end fastened to the lower end of the bracket 185. A pair of adjustable journal brackets 188, similar to 104 have supported therein the oscillating shafts 199 and 200, similar to 108 and 109. A lever with the arms 210 and 211, is fastened to the shaft 199. The rope 186 has one end fastened to the arm 210. A spring 214 similar to 114 has one end fastened to the arm 211, and its other end is fastened to the bracket 215 extending from the beam 22 of the frame B. A segmental gear 216 similar to 116 is fastened to the oscillating shaft 199, and a segmental gear 217 is fastened to the oscillating shaft 200. The teeth of 115 the latter mesh with the teeth of the segmental gear 216. A pair of clamping fingers 218 extend from the shaft 199 and a pair of clamping fingers 219 extend from the shaft 200.

A pair of guide rods 220 extend through 120 and have their ends supported in the cross beams 25 of the frames A and B. A cross head is designated in its entirety by the numeral 225. The cross head comprises the bottom plate 226 from which extend the guide lugs 227, with openings that engage the guide rods 220. A pair of lugs 228 extend from the lower face of the plate 226. End walls 229 extend up from the bottom 125 130

plate 226 and have formed therewith the top plate 230. A pair of bell crank levers are each designated at D and a second pair are designated at E. Each bell crank lever 5 comprises the members 235 and 236. Each of the members 236 are pivoted to the top plate 230 by means of a screw pivot 237. In each of the members 235 is formed an elongated guide opening 238, in which latter 10 is adjustably supported the threaded shank 239 of the pivot 240, by means of the nuts 241. Rollers 242 are journaled on the pivots 240. To each of the bell crank levers D and E is fastened a clamping bracket 245. Each 15 pair of said bell crank levers is connected by a spring 246. A guide plate 248 for each pair of bell cranks D and E extends from the top plate 230.

To the beams 39 is fastened a bracket 250, 20 in which is pivoted the lower end of the link 251. A link 252 is pinned to the upper end of the link 251, and is in turn pinned to the lugs 228 of the cross head 225. The connecting rod 95 is pinned to the link 251 by 25 means of the pin 253.

In the upper faces of the longitudinal beams 38 which are preferably of metal, are formed dove-tail guide openings for the dove-tail supports 258. Each support 258 30 has extending therefrom a threaded shank 259. The outer side faces of the beam 38 have fastened thereto the U shaped brackets 260, which have openings for the shanks 259. Nuts on the shanks 259 enables them 35 to be clamped in different positions, to vary the location of the dovetail supports in their guide openings. T shaped tracks 262 which converge toward their central portions 263, are fastened to the supports 258. Each of 40 the tracks is preferably straight for a short length at its central portion 263 as shown. The rollers 242 bear against the outer faces of the vertical members of the T shaped tracks 262. Turning rods 268, 269 are detachably connected to the clamping brackets 245 of the bell crank levers D, and turning rods 270 and 271 are detachably connected to the clamping brackets of the bell crank levers E. A receiving table 275 is located 45 within the frame A and an inclined chute plate 276 has its upper end fastened to the posts 30 and 31 of said frame. A receiving table 285 with its chute plate 286 respectively similar to 275 and 276 are provided for 50 the frame B.

To operate the double end bag turning machine, it is started by turning the pulley 83 by a belt not shown, and the bags which 55 have been previously turned inside out in the course of their manufacture are located one over the other upon the feed table 43. One of the bags is indicated at 288 (Fig. 1) with its open end 288^a and its bottom end 288^b, which the operator has removed from 60 the table 43, with its open end 288^a engaged

by the U shaped bag supporting bracket 54 and the D shaped arms 56 of the frame A. The arms 56 when the open end of the bag is engaged thereby are adjacent to the supporting bracket 54, and with the turning of 70 the shaft 90, the coaction of the cam 97, the lever 76, the connecting rod 66, the spring 73, the arm 65 and the oscillating shaft 52, the arms 56 are swung down and open the open end 288^a of the bag. To prevent injury 75 to the open end of the bag by the swinging down of the D shaped arm 56, the U shaped supporting bracket 54 swings down somewhat by reason of the open end of the bag bearing thereon. The supporting bracket 80 54 swings down against the tension of the spring 63. The object of making the arms 56 D shaped is to allow the turning rods 268 and 269 to clear them as they enter the bag.

The rotations of the spur gear 91 with 85 the shaft 90, through the connecting rod 95, swings the link 251 and thereby the cross head 225 slides toward the bag, and the turning rods 268 and 269 engage the lower member of the open end of the bag, and turn 90 it from its outside to its inside, and locate its closed end 288^b between the clamping fingers 118 and 119, as indicated in the frame B for another bag. While the turning rods 268 and 269 are moving to turn the 95 bags, their outer ends 288^a gradually spread, to laterally open the bag. The turning rods 268 and 269 are spaced by the coaction of the rollers 242 with the T shaped tracks 262. The rollers 242 bear against said tracks 262 100 and swing the bell crank levers D, which latter swing the said turning rods as they move with the cross head 225. After the bottom end of each bag is located between the clamping fingers 218 and 219, the latter 105 swing to clamp the said bottom end 288^b as indicated for another bag in frame B (Figs. 1 and 2). The fingers 118 and 119 open and close by the coaction of the cam 98, lever 100, bracket 101, rope 102, and the arm 110, 110 by means of which the shaft 108 is oscillated. The oscillations of the shaft 108 are transmitted to the shaft 109 through the intervention of the segmental gears 116 and 117. The fingers 118 and 119 are closed 115 through the coaction of the spring 114 with the arm 111. When the bottom end of the bag is clamped by the clamping fingers 118 and 119, the cross head 225 recedes from the turned over bag and the turning rods 268 120 and 269 are withdrawn therefrom and are located in their initial position as indicated in Figs. 1 and 2. Next the clamping fingers 118 and 119 open and the bags one after the other are deposited upon the receiving table 125 275.

The operations of the bag turning appurtenances associated with the frame B are the same as described for the frame A.

It will be noted however that when the 130

turning rods 268 and 269 associated with the frame A begin turning one of the bags, the clamping fingers 218 and 219 release the bag that has been turned by the turning rods 270 and 271 of the frame B and are dropped upon the receiving table 285 of the frame B. In other words the appurtenances associated with both pairs of the turning rods 268, 269 and 270, 271 are continuously operating. 10 Various modifications may be made in the invention and the present exemplification is to be taken as illustrative and not limitative thereof.

Having described my invention what I 15 desire to secure by Letters Patent and claim is:

1. In a bag turning machine the combination of a reciprocating cross head, a pair of turning rods for the cross head, means to 20 laterally swing the turning rods as they reciprocate with the movements of the cross head, means to support and spread the open end of each bag operated upon and locate it in proper position for the turning rods to 25 enter the same, a pair of shafts in the machine, a pair of clamping fingers extending from each shaft, a lever with a pair of arms extending from one of said shafts, an oscillating lever pivoted in the machine, a connection 30 between said lever and one of said arms to swing the latter and thereby one pair of said clamping fingers, a spring with one end thereof fastened to one of the arms of said lever and its other end fastened in 35 position in the machine, and a segmental gear on each shaft, said gears meshing with each other.

2. In a bag turning machine the combination of a reciprocating cross head, a pair of 40 turning rods carried by the cross head, means to laterally swing the turning rods as they reciprocate with the cross head, means to support and spread the open end of each bag operated upon and locate it in proper 45 position for the turning rods, a pair of shafts supported in the machine, a pair of clamping fingers extending from each shaft, a lever with a pair of arms extending from one of said shafts, a second lever pivoted in 50 the machine, a cam rotating in the machine coacting with the second lever to oscillate it, a connection between the second lever and one of the arms of the first lever, a spring with one end fastened to the other arm of the 55 first lever and its other end fixed in the machine and segmental gears on the said oscillating shafts with their teeth meshing with each other.

3. In a bag turning machine the combination 60 of a reciprocating cross head, a pair of

bell crank levers with one member of each pivoted to the cross head, a pair of tracks in the machine, means to locate the tracks in different operative positions, a roller connected to the other member of each bell 65 crank lever bearing against one of said tracks, a turning rod carried by each bell crank lever, means to locate each bag operated upon in proper position for said turning rods and means to clamp the bottom or 70 closed end of each bag after having been turned as described.

4. In a bag turning machine the combination of a reciprocating cross head, a pair of bell crank levers with one member of each 75 pivoted to the cross head, a runway frame comprising a pair of longitudinal beams in the machine, a plurality of supports slidably supported in each of said beams, means to clamp said supports in different positions, a track fastened to the said supports of each beam of the runway frame, a roller connected to each other member of the bell crank levers bearing against said tracks, means to 80 locate the open end of each bag operated upon in proper position for the turning rods and means to clamp the bottom or closed end of each of said bags after having been 85 turned substantially as described.

5. In a double end bag turning machine 90 the combination of a pair of end frames, a runway frame interposed between said end frames, a reciprocating cross head for the runway frame, two pairs of turning rods for the cross head, each pair of turning rods oppositely positioned to the other pair, means to laterally swing each pair of turning rods as they reciprocate with the cross head, a pair of oscillating shafts associated with each end frame, a pair of arms for one of 100 said shafts, means to oscillate the latter shaft, a supporting bracket for the shaft of said pair, means to maintain the supporting bracket in tensional relation with said arms, said bracket and said arms adapted to open the open ends of the bags operated upon, a second pair of oscillating shafts associated with each end frame, a pair of clamping fingers for each of the latter oscillating 105 shafts, segmental gears interposed between each pair of the latter oscillating shafts, a lever with a pair of arms for one of the shafts of each latter pair, means to swing one of the arms of each of said levers and means to maintain the other arm of each of the said levers in tensional relation with its other arm.

In testimony whereof I affix my signature.

LOUIS J. CONTRESSA.
